G. SCHMID

BRIDGE

Filed Dec. 17, 1923

INVENTOR.
BY *GEORGE SCHMID*.
Richard Brown.
ATTORNEY.

UNITED STATES PATENT OFFICE.

GEORGE SCHMID, OF NEW YORK, N. Y.

BRIDGE.

Application filed December 17, 1923. Serial No. 681,245.

This invention relates to bridges for stringed musical instruments and has for its object to provide, what may be termed a practice bridge wherein the tone of the 5 strings may be subdued to a minimum degree.

One of the objects of my invention is to provide a practice bridge adapted for use on violins and other stringed instruments 10 without interfering with bowing, said bridge being preferably constructed of soft metal, such as lead, whereby the vibration of the strings and the sound emitted is reduced to a minimum for practice purposes.

15 To enable others skilled in the art to fully comprehend the underlying features of my invention that they may embody the same in the various modifications in structure and relation contemplated, drawings depicting a 20 preferred form have been annexed as a part of this disclosure and in such drawings, similar reference characters denote corresponding parts throughout all the views, of which,

25 Figure 1 is a vertical section through the head and base of the bridge showing the supporting post connecting the same.

Figure 2 is a view of the base and the supporting post of a modified form of the invention.

30 Figure 3 is a modified form of the invention.

Figure 4 is a modified form of insert for the head.

35 Figures 5, 6 and 7 are various modified forms of heads and inserts for different stringed instruments.

40 Referring now to the drawings wherein like reference characters designate corresponding parts throughout the several views, my novel and improved bridge is constructed preferably of metal which will absorb the vibration of the strings thus reducing the volume of the tone emitted and having adjustable features which permit of the raising 45 and lowering of the bridge head to obtain different volumes of sound. It will be understood from the beginning that the bridge may be made in various sizes for use on different types of stringed instruments 50 and that the design may be altered to suit different conditions that may exist depending upon the character of the instrument. The bridge is composed of two parts, namely the head, or upper part 5 and the lower part or base 6. Both of these parts are preferably made of lead, solder, spelter, Babbitt

or any other soft metal which will absorb vibration, but of these metals, it has been found that lead has been most desirable. The head 5 may be formed with a bell-shaped bottom 7 and is provided with a transverse groove or slot in the top thereof to receive a notch insert 8, preferably of spelter, it being found that spelter is more suitable for resisting cutting, incident to the 65 strings when the same are drawn very taut. The spelter is milled as shown so as to permit the strings to rest in the grooves 9 at the desired position.

The supporting post 10 is constructed of 70 highly tempered steel, which reduces the vibrations of the strings to a minimum without sacrificing strength and is preferably threaded for a portion of its length as indicated at 11 and extends through a thimble 75 12 inserted within the bottom of the head above referred to. The thimble is preferably formed with lugs 13, which prevent the rotation or turning of the head with respect to the thimble. The head is also provided 80 with a reduced cap portion 14 to permit the sounding post to freely pass therein as the head is being lowered. The supporting post is preferably formed integral with a square, 85 flat-foot portion 15 within the body of the base adjacent the top thereof. A stabilizing and locking washer 16, threaded on the post is adapted to bear against the under surface or bottom face of the bell-shaped head 7 so as to prevent the head from being distorted 90 by reason of the downward pressure of the strings of the instrument.

In Figure 2 of the drawings, it will be seen that the base 6^a is similar to the base shown by Figure 1 with the addition that the 95 spherical shaped feet 16^a permit the base to be raised somewhat from the body of the instrument when the bridge is positioned, it being observed that the supporting post and the flat foot are the same as that shown in 100 the above figure.

In Figure 3 of the drawings, the square head 17 is also provided with an insert 18 of spelter but in this form of the invention two supporting posts 19, 20, similarly threaded as the supporting post 10, are provided and the feet of said posts are imbedded in lead casts 21, 22. The vertical caps 23, 24, 105 permit the post and the casts to be threaded in the thimbles consequently raising and 110 lowering of the head 17 to the desired degree to lessen or increase the volume of

sound. In this form of the invention it will also be seen that the thimble and stabilizing washers are provided for the obvious purposes as above described in connection with 5 Figure 1 of the drawings. In Figures 4, 5, 6 and 7, I have shown various designs of bridge heads such as the circular-shaped head 28, 29, is provided with a spelter insert frusto-conical top edge 27 whereas in Figures 5 and 6, a square and triangular shaped head 28, 29, is provided with a spelter insert having a flat top surface. In Figure 7, a bell-shaped head 30, with a spelter insert, somewhat similar to that shown by Figure 15 1, may be utilized being especially adapted for the bass and cello group of stringed instruments.

While I have illustrated and described my invention with some degree of particularity, 20 I realize that in practice various alterations therein may be made. I therefore reserve the right and privilege of changing the form

of the details of construction or otherwise altering the arrangement of the correlated parts without departing from the spirit of 25 the invention or the scope of the appended claim.

Having thus described my invention what I claim as new and desire to secure by 30 United States Letters Patent is:—

A bridge for musical instruments comprising a head having a groove therein, a string supporting piece in said groove, said head having a bore therein, a sleeve in the bore, 35 projections on the sleeve for preventing turning movement thereof, a threaded spindle operable through said sleeve to raise and lower the head, a base, an enlarged foot member on the spindle positioned in said base and a lock nut on the spindle for maintaining the 40 head in its adjusted position.

In testimony whereof I affix my signature.

GEORGE SCHMID. [L. S.]
